UNITED STATES PATENT OFFICE.

FRANK A. WEEKS, OF PLAINFIELD, NEW JERSEY.

INKSTAND.

Application filed May 24, 1922. Serial No. 563,449.

To all whom it may concern:

Be it known that I, FRANK A. WEEKS, a citizen of the United States, and a resident of Plainfield, in the county of Union and 5 State of New Jersey, have invented certain new and useful Improvements in Inkstands, of which the following is a specification.

The invention relates to inkstands of the type comprising a glass base containing an 10 ink-holding chamber or well and a removable cover mounted thereon.

In accordance with my invention the glass base is of a form adapted to provide a commodious inkwell and has at opposite sides 15 of the upper end of said well integral upwardly projecting ribs which serve to locate the cover over the well and prevent both lateral and longitudinal movement thereof, while at the same time permitting the cover 20 to be lifted off from the base when it is desired to supply the well with ink. The glass base may also, when desired, be formed with a forward rest for pens and pencils.

My invention pertains more particularly 25 to a novel cover to be mounted upon the glass base over the inkwell, this cover being of special construction adapted to the ribs on the base and having in its forward central portion a dip-opening to admit a pen to the 30 well and a special pivotally mounted self-closing closure device therefor adapted to maintain said opening closed except while a pen is being introduced into and removed therefrom.

The invention will be fully understood 35 from the detailed description hereinafter presented, reference being had to the accompanying drawings, in which:

Fig. 1 is a top view of an inkstand embodying my invention;

Fig. 2 is a central vertical longitudinal section through the same, the closure device for the dip-opening in the cover being shown in normal closed position;

Fig. 3 is a corresponding section through 45 the same, with the closure device for the dip-opening shown partly in side elevation and partly in section in its open position;

Fig. 4 is a vertical transverse section 50 through the inkstand taken on the dotted line 4-4 of Fig. 2;

Fig. 5 is a bottom view of the cover removed from the glass base;

Fig. 6 is a like view of the main body portion of the cover, the closure device for the dip-opening and the frame for securing said

device to the body of the cover being omitted;

Fig. 7 is a detached perspective view of the closure device for the dip-opening, and 60

Fig. 8 is a like view of the frame for securing the closure device to the cover.

In the drawings 10 designates the glass base, 11 the cover mounted thereon, 12 the dip-opening in said cover, 13 the closure device for said opening, and 14 a frame which is finally fastened to the body portion of 65 the cover for securing said closure device in position and at the same time permitting the device to have an oscillatory or hinged 70 movement.

The base 10 is in one integral oblong glass block containing a commodious oblong chamber or well 15 for the ink and formed with a forward pen-rest 16, a main flat upper surface 17 and longitudinal upwardly projecting ribs 18, one rib being at each side of the upper end of the well 15 and extending beyond the front and rear walls thereof, as 80 shown in Figs. 2 and 3.

The cover 11 is of generally oblong outline suited to the base 10 and will be formed, usually, of composition material of the character commonly employed for inkstand-covers. The cover 11 has a curved forwardly projecting portion 19 and along its edges is formed with a downwardly projecting integral encompassing flange having a flat lower edge to rest firmly upon the flat upper surface of the base 10, said flange 90 comprising side members 20, a rear member 21 and a front member 22, whose end portions extend inwardly beyond the side members 20 and form opposite corresponding stop-shoulders 23 (Figs. 5 and 6) to 95 abut against the forward ends of the ribs 18 and thereby resist any thrust of a pen or other article tending to push the cover 11 rearwardly on the base 10. The rear flange member 21 is directly at the rear of the rear 100 ends of the ribs 18 and serves to close the space between said ends of said ribs and also to cooperate with the ribs in preventing forward sliding of the cover on the base 10.

The front flange member 22 closes the space 105 between the forward ends of the ribs 18 and conforms to the outline of and firmly supports the forward portion 19 of the cover on the base 10. The side flange-members 20 embrace the ribs 18 at their outer sides 110 and cooperate therewith in preventing lateral movement of the cover on the base 10.

The downwardly projecting encompassing flange on the cover serves to elevate the body of the cover from the base 10 and to firmly support the same thereon, and said flange in cooperation with the ribs 18 acts to prevent either longitudinal or lateral shifting of the cover after it has been positioned upon the base 10.

In its central forward portion the cover 11 is formed with the opening 12 which is oblong in outline and forwardly-rounded at its front end, at which the cover is formed with a downwardly and inwardly surface-curved flange 24 whose lower surface inclines upwardly and rearwardly, as shown in Figs. 2 and 4, to form a seat 25 for the forward end portion of the closure-device 13 when said device is in its closed position, as shown in Fig. 2. The flange 24 laps over upon the forward end of the closure-device 13 and serves as a cover therefor as well as to provide on its lower surface a seat or stop for the said device when the device turns to its closed position. The opening 12 has the rounded forward end hereinbefore referred to and back thereof, parallel side walls which are connected at their rear ends by a back wall 26. The opening 12 is throughout encompassed by the material of the cover 11 and therefore lies wholly within said cover, and the forward portion of said opening is adapted to admit a pen to the ink within the well 15.

Within the opening 12 I mount the closure device 13, which is of oblong formation and has a forward tongue portion 27 and a thickened and thereby weighted rear portion 28 whose opposite sides are formed with trunnions 29 adapted to rounded bearings 30 formed in the cover 11 below its upper surface and extending outwardly from the opposite side walls of the opening 12. The cover 11 is formed in its bottom along the sides and rear end of the opening 12 with a three-sided recess 31, and it is at the top of the opposite sides of this recess that I form the bearings 30 to loosely receive the trunnions 29. In assembling the cover parts and applying the closure device 13 to position in the opening 12, I turn the said device to stand at right angles to the opening 12 and then insert the same endwise transversely into said opening and seat the trunnions 29 in the bearings 30, and thereafter I turn the device 13 longitudinally of and within the opening 12 and secure the same to the cover by a three-sided frame 14 (Fig. 8) which I rigidly cement or otherwise fasten within the conforming recess 31 of the cover, thereby completing the cover and securing the closure device permanently thereto.

The closure device 13 lies wholly within the cover 11 or in other words at no time extends beyond the ends or sides thereof and

hence is protected against accidental operation and permits the cover to have continuous edge walls seated on the flat upper surface 17 of the base 10. The securing frame 14 and bearing recesses 30 while permanently housing the trunnions 29 permit said trunnions to have rotary motion in said recesses 30, and in consequence thereof the closure device 13 becomes pivotally mounted within the opening 12 of the cover. The weighted rear portion 28 of the closure device 13 acts automatically to turn the lighter forward tongue portion 27 of said device to closing position below the stop or seat 25 on the cover and hence normally the opening 12 is entirely closed by said device, as shown in Figs. 1, 2 and 5, said device being proportioned to properly fill said opening.

When it is desired to take ink on a pen-point, the pen will be pressed downwardly against the forward end of the closure device 13, and this will cause said end to turn downwardly (Fig. 3) in opposition to the resistance offered by the weighted end 28 and admit the pen to the well 15. When the pen is withdrawn from the well 15 and opening 12, the weighted end 28 of the closure device will tilt said device to its normal closing position shown in Fig. 2, the opening 12 then being closed and evaporation of the ink or the entrance of dust thereto being prevented. I so locate the opening 12 that a pen inserted through the same to take ink from the well 15 has no opportunity to strike any side wall of the well, the thrust of the pen being downwardly and rearwardly into the forward portion of well.

The inkstand of my invention comprises two main units, to-wit: the elongated base and the elongated cover, and these two parts are so formed and related that they constitute a desirable inkstand for use on an office desk. The inkstand cannot be tilted over by any ordinary treatment, or accident, and the top of the cover is left smooth or without projecting portion to catch upon any object that might be moved or slid over the same. The relative form and association of the cover and the closure device for the opening 12, therein, as hereinbefore defined, are features of importance in the production of a permanently useful, convenient and desirable desk-inkstand.

It is desirable that the closure-device 13 lies substantially horizontal when in its closed position, and to this end the flange 25 should be as shallow as consistent with requisite strength so as to eliminate as far as possible the presence of a recess in the top of the cover.

What I claim as my invention and desire to secure by Letters Patent, is:

An inkstand comprising a base containing a well for ink and a cover mounted on said base over said well containing in its

central forward portion an elongated opening extending close to the forward portion of the cover, said cover being formed in its bottom along the sides and rear end of said opening with a three-sided recess and above the sides of said recess with bearing recesses normally opening downwardly into the same, said cover having within said opening an elongated tiltable self-closing substantially horizontal closure-device therefor

comprising a forwardly extending tongue, a weighted rear portion and side trunnions within said bearing recesses, and said cover having a three-sided frame fastened within said three-sided recess and closing said bearing recesses from below. 15

Signed at New York city, in the county of New York and State of New York, this 23rd day of May A. D. 1922.

FRANK A. WEEKS.
